US0D1091179S

(12) **United States Design Patent** (10) **Patent No.:** **US D1,091,179 S**
(45) **Date of Patent:** **** Sep. 2, 2025**

(54) **DISPENSER FOR SOAP AND SANITIZER**

(71) Applicant: **SATELLITE INDUSTRIES, INC.**, Minneapolis, MN (US)

(72) Inventors: **Everett A. Spandl**, Dahlonega, GA (US); **Kenneth V. Schomburg**, Plymouth, MN (US)

(73) Assignee: **Satellite Industries, Inc.**, Minneapolis, MN (US)

(**) Term: **15 Years**

(21) Appl. No.: **29/923,301**

(22) Filed: **Dec. 28, 2023**

(51) **LOC (15) Cl.** **23-08**

(52) **U.S. Cl.**

USPC **D6/545**

(58) **Field of Classification Search**

USPC D6/515, 522, 542, 512, 518, 520, 524, D6/543, 544, 545; 206/233, 389, 401, 206/77.1, 581, 225, 229; 211/45, 48, 211/88.04, 119.009, 85.12; 221/26, 208, 221/282, 283

(57) **CLAIM**

The ornamental design for a dispenser for soap and sanitizer as shown and described.

DESCRIPTION

FIG. 1 is a perspective view of a dispenser for soap and sanitizer showing the claimed design;

FIG. 2 is a first side view of the dispenser for soap and sanitizer of FIG. 1;

FIG. 3 is a second side view of the dispenser for soap and sanitizer of FIG. 1 that is opposite the first side of FIG. 2; FIG. 4 is a top view of the dispenser for soap and sanitizer of FIG. 1;

FIG. 5 is a bottom view of the dispenser for soap and sanitizer of FIG. 1;

FIG. 6 is a front view of the dispenser for soap and sanitizer of FIG. 1; and,

FIG. 7 is a rear view of the dispenser for soap and sanitizer of FIG. 1.

The broken lines in the drawings represent unclaimed subject matter and form no part of the claim.
